UNITED STATES PATENT OFFICE.

FRANK D. SHEPHERD, OF SALT LAKE CITY, UTAH.

STEAM-TURBINE.

SPECIFICATION forming part of Letters Patent No. 728,138, dated May 12, 1903.

Application filed June 23, 1902. Serial No. 112,911. (No model.)

To all whom it may concern:

Be it known that I, FRANK D. SHEPHERD, of Salt Lake City, in the county of Salt Lake, and in the State of Utah, have invented certain new and useful Improvements in Steam-Turbines; and I do hereby declare that the following is a full, clear, and exact description thereof, reference being had to the accompanying drawings, in which—

10 Figure 1 is a side elevation of a steam-turbine embodying my invention. Fig. 2 is an end elevation of the same. Fig. 3 is a vertical longitudinal section of the turbine. Fig. 4 is a cross-section on the line 4 4 of Fig. 3. Fig. 5 is a detail view in cross-section on the line 5 5 of Fig. 3. Fig. 6 is a horizontal section on the line 6 6 of Fig. 5. Fig. 7 is a detail view in perspective of one of the inlet port-blocks, and Fig. 8 is a detail view showing in perspective one of the high-pressure piston-blades and one of the low-pressure piston-blades.

15 The object of my invention is to provide a simple, efficient, and economical engine or motor of the rotary type, and to such end my invention consists in the engine having the construction substantially as hereinafter specified and claimed.

In the embodiment of my invention I have selected for illustration I construct the body of the engine of sections, preferably three, two similar end ones A and A and a middle one B, that are firmly secured together by parallel rods C, that run through alining 35 holes in the sections and on their ends have nuts D. On the bottom of each section, except on the sides where the sections abut, are flanges, which together form a base for mounting and securing the engine to its bed. Each 40 of the sections has a horizontal cylindrical opening or chamber through it, and at each end of the body to close the opening thereat is a head E, that is held in place by the rods C and the nuts D. To secure steam-tight 45 joints between the abutting surfaces of the sections and heads, complementary ribs and grooves are formed on their adjacent surfaces and a thin sheet of packing is placed between a rib and its groove, the latter being 50 made slightly deeper than its rib to receive the packing.

Concentric with and passing through the

cylinders which the sections form is a shaft F, having bearings in the two heads E and E and in the packing of stuffing-boxes e and e of usual construction on the respective heads. Keyed to the shaft at a point midway between the ends of the middle section or cylinder B is a disk G, that forms a division-wall or partition, and on each side of said disk is a series of disks or collars H, as shown, three, from the periphery of each of which radiates a series of blades h, their outer ends reaching to the interior surface of the cylinder, said disks or collars being likewise keyed 60 to the shaft and separated or spaced apart by collars I. On the shaft between the end disk H of each series and the cylinder-head adjacent thereto is a sleeve K, its end next the disk being preferably flanged or enlarged in 65 diameter to about that of the disk. A setscrew k serves to fix the position of the sleeve on the shaft, and between the two sleeves the disks and collars are confined or held against movement along the shaft. A single 70 long key f is used to fix all of the disks and collars on the shaft F, and its length is such that its ends do not project beyond the end disk H, so that the sleeves K will abut against said end disk H, and thereby all of the disks 75 and collars be maintained in proper position on the shaft.

Steam is admitted to the cylinder-section B on each side of the partition or division disk G and at two diametrically opposite points, an 80 inlet-port being provided for each side. Said inlet-ports l are most conveniently made in pairs in a block L, set in a cavity in the cylinder-section B, so that said ports will extend in lines tangential to the interior wall of the cylinder, the inner end of the block through 85 which the ports emerge being curved coincident with the curvature of the interior wall of the cylinder. At its opposite end the block has a slot or recess forming a steam-chamber 90 l', common to the two inlet-ports. The ends of the ports opening into said chamber are preferably enlarged or countersunk, and said ports are gradually enlarged in diameter to their inner or discharge ends. The latter by 95 reason of their terminating or the curved walls of the inner wall of the cylinder have an elliptical form. The blocks L are scraped and fitted in steam-tight. They can be changed 100

when for any reason it is desired to change the size of the ports, blocks with ports of a different size being substituted for those already in use.

- 5 Communicating with each steam-chamber l' is a steam-pipe M , having a hand-valve N , and the two pipes M and M are connected with a main pipe O from the boiler. In the main pipe is placed the governor, which may 10 be of any desired construction. I employ and illustrate in the drawings a horizontal governor P of the spring-and-ball type, which is belted to the shaft F , a belt being run from a small pulley Q on said shaft to a large pulley R on the governor-shaft. Such a governor and so geared gives splendid results; but it is to be understood that I do not limit myself to any particular kind or arrangement 15 of governor.
- 20 It will be perceived that the location of the governor in the main steam-pipe insures uniform regulation of the steam-supply to the two sets of inlet-ports. Any adjustment that may be required of the steam supply or pressure 25 of the two sets of ports can be effected by means of the hand-valves N .

It will be seen that steam entering the cylinder-section B through the ports l will impinge on the blades h of the disk that is next 30 the division or partition disk G , and then moving from said disk G will pass in an axial direction to and past the blades of the other disks of the series to the ends of the cylinder-sections A and A , which constitute exhaust-chambers having each an exhaust-port and from which run pipes S and S , connected to a common discharge-pipe S .

The blades h have their rear surfaces or those past which the steam flows in moving 40 in an axial direction dished or concave and their front surfaces curved convexly, so that the shape of each blade in cross-section is substantially that of a crescent. The blades are set so that their general position is inclined or oblique to the plane of the shaft-axis, the larger portion of the dished or concave surface being so inclined that the steam in passing across it will impart rotary motion to the shaft. The convex forward surfaces 45 of the blades adjacent the edge from which the steam passes are more abruptly inclined in the same direction, so as to reduce to a minimum the retarding effect of the steam on their revolution. The blades of the disks 50 next the partition-disk G have their edges next the latter in close contact therewith to prevent steam passing between them and said disk G , and thus compel all of the steam to move in an axial direction from the disk G 55 across the concave inclined surfaces of the blades.

60 Into the spaces between the blades of adjacent disks blades t , similar in form to the blades h , project radially inward from rings T , situated in enlargements of the cylinders, spacing-rings U being placed between the rings T . The internal diameter of these

70 rings is the same as the diameter of the cylinders. Said rings are held from turning by having notches in their peripheries that engage ribs or projections a on the walls of the cylinder-sections A . The blades t slant in directions that intersect the directions of slant of the blades h , and their concave or dished sides are toward the like sides of the 75 adjacent blades h , so that steam passing from the blades h of one disk H will engage and be directed by the blades t to the blades h of the next disk H . To insure that all steam shall pass from one set of blades h to the 80 next, the diameter of the collar between adjacent disks H is less than that of the disk from whose blades the steam passes, and the blades t , encircling said collar, are made long enough to fit said collar closely. They therefore project beyond the periphery of the disk having the blades from which the steam is passing and accordingly steam must have contact with their sides in passing and be directed to the next disk-blades h . The reduction of the diameter of the collars by increasing the space between the blades t provides for the increase in the volume of steam from expansion, and for the same purpose 85 the disks H are successively reduced in diameter.

90 Preferably the blades h of the disks on one side of the partition-disk G are arranged to come in line in an axial direction with the spaces between the blades on the opposite side of said disk, so that the blades on opposite sides of the partition-disk will not receive the steam simultaneously, but successively, or one set after another.

95 The outer ends of the blades h , that traverse the inlet-ports, are cut away, preferably in a convexly-rounded form, on their forward sides. Thus a blade passing the port will interfere as little as possible with the passage of steam to the preceding blade, and the elongated form and position of the discharge end of the port contribute to this result. The outer ends of the other blades h are curved in correspondence with the curvature of the cylinders and fit the latter sufficiently close 105 for skin-friction only.

110 As a convenient and desirable mode of attaching the blades to their respective disks and rings the latter have dovetailed notches or slots in their peripheries, and the blades 115 have like-shaped tenons or projections that are driven into the slots and brazed. The blades being as wide as the disks or rings, as the case may be, even though the blades 120 should become loose by accident, they could 125 not become displaced sidewise, since they are covered or engaged on both sides.

130 The operation of my engine is as follows: Steam is admitted to the chambers l' and passes through the inlet-ports into the first or high-pressure cylinder simultaneously upon opposite sites of the partition-disk and at diametrically opposite points in each of the two divisions of said cylinder, striking

the blades of each of the pistons therein with great force and each blade in succession receiving the full pressure of the steam and no back blow or pressure to a following blade being given by reason of the position of the ports and the form of the blades. Each piston receiving the steam at diametrically opposite points is subjected to a balanced pressure, which reduces friction and wear and helps overcome vibrations. From the blades of the two high-pressure pistons the steam travels or exhausts into the spaces between the directing-blades *t* and is guided by them to the blades of the next or lower-pressure cylinder and from the latter to the spaces between the next series of directing-blades, by which it is guided to the succeeding piston-blades, leaving which it enters the exhaust-chambers and passes therefrom through the exhaust-ports.

It will be seen that by reason of the form and position of the piston-blades the steam will act by its direct impact thereon in the direction of revolution of the pistons to revolve the pistons and also by its travel or passage across and in contact with the blades in an axial direction.

By reason of the duplication of the pistons and the interposition between them of the partition-disk *G* endwise pressure or pressure in an axial direction on the pistons is balanced by the equal pressure in opposite directions on opposite sides of said disk. This not only makes the engine run easy and avoids wear, but maintains the piston-blades *h* in proper relative position to the steam-guiding blades *t* and obviates possibility of the former striking and cutting the latter. Should, however, there be any unbalanced pressure tending to produce endwise movement, such will be opposed by the sleeves *K* at the ends of the series of pistons. Though screws are used for holding said sleeves in position, the contact of the sleeves with the cylinder-heads is depended on rather than the screws to take care of any endwise pressure that might exist. The fit of the disk *G* in the cylinder is such that when it is expanded from the high temperature and revolving at a high speed the joint is practically steam-tight and there is skin-friction only.

As the exhaust from both exhaust-chambers is to and through a common pipe, the pressure in the two chambers will be the same, and thus the balanced condition of the pistons will be unchanged, and this is so whether the exhaust is to the atmosphere or into the vacuum of a condenser.

It will be noted that the reduction in diameter of the disks of the successive pistons provides for the increasing volume of steam as it expands.

The form of the forward or advancing sides of the blades is such that pressure upon them tending to oppose the revolution of the pistons is reduced to a minimum.

It will be observed that the steam acts expansively upon the blades of the high-pressure pistons undergoing expansion as it travels with the piston-blades from one inlet-port to the next and that it also acts expansively upon the blades of the successive low-pressure pistons. The steam in passing through the inlet-ports also expands by reason of the tapering form of said ports, such form of the ports reducing friction and increasing the velocity of the steam.

The engine I illustrate is a triple-expansion one; but of course the invention is not restricted to the adaptation of the engine to any number of expansions, as these may be varied as desired. The number of expansions to secure the greatest economy in steam will depend on the size of the engine, the size of ports used, and the steam-pressure. As the construction I have devised is adaptable to the utilization of the steam to its utmost limit of expansion, my engine is most economical.

It will be seen that my engine is balanced, double-acting, has adaptability to numerous expansions of steam, is economical of steam, and of extremely simple construction.

It is to be understood that fluids under pressure other than steam may be used with my engine, and I therefore do not restrict the scope of my invention to a steam-driven motor.

Having thus described my invention, what I claim is—

1. The combination of a cylinder, a partition having a diameter to fit the cylinder, a series of simultaneously-driven rotary pistons having inclined fluid-engaging blades on both sides of the partition, the latter being opposite the blades, the inclination of the blades being oblique to the piston-axis, and inlet-ports on opposite sides of the partition.

2. The combination of a cylinder made of separable sections, a series of rotary pistons comprising each a disk with peripheral blades, stationary blades projecting into the spaces between the blades of different disks, rings to which said stationary blades are attached, situated in spaces between the cylinder-sections, said spaces being formed by enlargements of the cylinder-sections.

3. The combination of a cylinder made of separable sections, a series of rotary pistons comprising each a disk with peripheral blades, stationary blades projecting into the spaces between the blades of different disks, rings to which said stationary blades are attached, situated in spaces between the cylinder-sections, said spaces being formed by enlargements of the cylinder-sections, and ribs or projections on the cylinder-sections that engage notches in said rings.

4. The combination of a disk, or like part, peripheral blades connected therewith by dovetailed slots on one part, and corresponding projections on the other, the slots extending parallel with the axis of the disk, and opening to the side thereof, and a collar or

ring next the disk and overlapping the slots and projections therein.

5. The combination of a cylinder, rotary pistons, a partition between the pistons, and a removable block having ports leading directly to the cylinder on both sides of the partition.

6. The combination of a cylinder, rotary pistons, a partition between the pistons, and a removable block having ports leading to both sides of the partition, the block being recessed to form a chamber common to the ports.

7. The combination of cylinders, a shaft passing through them, a series of disks on the shaft, one of which forms a partition and the

others have fluid-engaging blades and are on both sides of the partition-disk, and are of different diameters, collars between the blade-carrying disks, fluid-guiding blades projecting into the spaces around the collars, sleeves on the shaft at both ends of the series of disks, inlet-ports having a common supply and exhaust-ports having a common discharge.

In testimony that I claim the foregoing I have hereunto set my hand this 28th day of 25 May, 1902.

FRANK D. SHEPHERD.
